CLAIM

I claim the ornamental design for food container, as shown.

DESCRIPTION

FIG. 1 is a perspective view of a food container, according to the present invention;

FIG. 2 is a front elevational view of the food container of FIG. 1, with a rear elevational view being a mirror image thereof;

FIG. 3 is a left side view of the food container of FIG. 1, with a right side view being a mirror image thereof;

FIG. 4 is a top end view of the food container of FIG. 1; FIG. 5 is a bottom end view of the food container of FIG. 1; FIG. 6 is a cross-sectional view of the food container taken along line 6-6 of FIG. 3;

FIG. 7 is a perspective view of a food container, according to an embodiment of the present invention;

FIG. 8 is a front elevational view of the food container of FIG. 7, with a rear elevational view being a mirror image thereof;

FIG. 9 is left side view of the food container of FIG. 7, with a right side view being a mirror image thereof;

FIG. 10 is a top end view of the food container of FIG. 7; FIG. 11 is a bottom end view of the food container of FIG. 7; and,

FIG. 12 is a cross-sectional view of the food container taken along line 12-12 of FIG. 9.

The design of FIGS. 7-12 corresponds directly to that of FIGS. 1-6 except for presenting a series of circumferentially spaced offset body portions in broken lines which form no part of the claimed invention for this embodiment.
